UNITED STATES PATENT OFFICE.

GARDINER S. BOWDEN, OF BROOKLYN, NEW YORK, ASSIGNOR TO J. B. BOWDEN & CO., OF NEW YORK, N. Y., A COPARTNERSHIP COMPOSED OF MARTIN L. BOWDEN, MARTIN L. BOWDEN, JR., AND GARDINER S. BOWDEN.

DESIGN FOR A RING.

Application filed August 28, 1923. Serial No. 7,109. Term of patent 3½ years.

To all whom it may concern:

Be it known that I, GARDINER S. BOWDEN, a citizen of the United States, and resident of the borough of Brooklyn, in the city and State of New York, have invented a new, original, and ornamental Design for a Ring, of which the following is a specification, reference being had to

the accompanying drawing, forming part thereof.

The figure is an elevation of my new design for a ring.

I claim:

The ornamental design for a ring substantially as shown.

GARDINER S. BOWDEN.
